UNITED STATES PATENT OFFICE.

LUKE KIRAL, OF BROOKLYN, NEW YORK.

MOVING-PICTURE-PROJECTING MACHINE.

Application filed November 3, 1924. Serial No. 747,624.

To all whom it may concern:

Be it known that I, LUKE KIRAL, a citizen of United States, residing at Brooklyn, in the county of Kings and State of New York, have invented new and useful Improvements in Moving-Picture-Projecting Machines, of which the following is a specification.

This invention relates to moving picture projecting machines and has for its primary object, the provision of an attachment for preventing the film from being ignited should the film break during the showing of the same.

Another object of the invention resides in a means for automatically closing the shutter of a moving picture projecting machine while the machine is in operation, upon the breaking of the film, thereby protecting the film from the heat of the arc lamp.

A further object resides in the provision of an attachment for moving picture projecting machines which will eliminate the fear of fire upon the breaking of the film, and which may be readily applied to the machines now in use without necessitating a change in a design of the machine.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a side elevation of a moving picture projecting machine with my invention applied thereto.

Figure 2 is an enlarged side elevation of a portion of a moving picture projecting machine showing the position when the shutter is raised in full lines, and the dotted lines illustrating the position of the parts when the shutter is in a lowered position.

Figure 3 is an end elevation.

Figure 4 is a horizontal sectional view on the line 4—4 of Figure 3.

Figure 5 is an enlarged detail view of the shutter actuating means.

Figure 6 is a sectional view through the friction wheels on the line 6—6 of Figure 3.

Referring more particularly to the drawings, the reference character A designates the lamp-house of a moving picture projecting machine, B a film magazine, C a second film magazine in which the film is wound

after passing from the magazine B across the usual film opening. The take-up sprocket D is positioned between the magazines for feeding the film from one magazine to the other. The usual shutter E is pivotally mounted as at F in a shield or housing G and which shutter is normally held open during the operation of the machine by a friction wheel H, and an arm J pivoted to the wheel, and an arm K carried by the shutter. The mechanism so far described is old in the art, but a more detailed explanation of the same will be given hereinafter.

The friction wheel H comprises a pair of sections 10 and 11, the section 11 of which is keyed to a shaft 12 which receives its power from a set of gears in the usual manner. The outer section 11 is formed with an annular collar 13 which extends within the outer section and serves as a bearing for a pair of sliding weights 14, carrying shoes 15 for co-action with the outer flange 16 of the section 10 when the wheel is travelling at a high rate of speed whereby the two sections are rotatable simultaneously for a predetermined distance. Springs 16' serve to normally hold the shoes out of contact with the flange 16.

My invention comprises a member 17 having side arms which are pivotally mounted upon the take-up sprocket shaft 18 and which straddle the take-up sprocket D. The lower end of the member supports a roller 19 over which the film M passes. A link 20 has one end pivotally connected to one of the side arms 17, and its other end connected with one arm of a bell crank lever 21, which arm is disposed within the frame or casing 22 of the machine. The other arm of the bell crank lever is disposed outside of the casing by forming the lever of two separate arms and keying them to a shaft 23 having its bearings in the casing 22 and in a bracket 24 secured to the outside of the casing. A link 25 connects the outside arm of the bell crank lever with the section 10 of the friction wheel H, the free end of the link having a slot 26 therein for connection with a pin or screw 27 extending from the section 10. A spring 28 is supported by the shaft 23 and has one of its ends co-acting with the pivot connecting the link 25 with the bell crank lever and its other end resting against a pin projecting from the casing of the machine. The spring acts to place a

tension on the member 17 when the film is in engagement therewith. The outward movement of the member being limited by the outside arms of the bell crank lever abutting the bracket 24. The link 25 is bent in a manner not to interfere with the mechanism on the outside of the frame, but it will be noted that the same may be straight if desired by slightly changing the position of 10 certain parts.

In practice, we shall presume that the machine is motionless, at which time the shutter E is in a closed position while the member 17 is held depressed against the tension of the spring 28 by the film M, and the link 20, bell crank lever 21 and link 25 are in the position shown in full lines in Figure 2 of the drawing. As the machine is set in motion, the shaft 12 will be caused 20 to rotate by reason of the usual gearing connected with the power shaft and as the shaft rotates, the centrifugal force will cause the shoes 15 to frictionally engage the flange on the section 10, thereby causing the said 25 section to move a slight distance sufficient to move the arm J forward to swing the shutter E about its pivot F to an open position and to hold the same in an open position as long as the disk is rotated. The machine is now in operation and the film is 30 being fed from one magazine to the other. Should the film break, the tension on the member 17 will cease and the member will swing to the position shown in dotted lines 35 in Figure 2 by reason of the spring 28. As the member moves forward, the link 25 is also moved in the same direction, thus causing the section 10 of the friction disk to rotate a slight distance in the direction 40 of the arrow shown in Figure 2 which causes the arm J to be retracted, at which time the shutter E will automatically drop to a closed position by reason of its own weight thereby 45 protecting the film from the heat of the arc which is arranged within the lamp housing, and which gives out intense heat sufficient to ignite the film in the event that the shutter did not instantly drop to a closed position. Heretofore the shutter was not 50 dropped until the speed of the machine had

been reduced to cause the sections of the friction disk to disengage, and which was not quick enough to prevent the ignition of the film.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:

1. An attachment for moving picture projecting machines comprising a member adapted to be pivoted to the take-up sprocket shaft of the machine, a bell crank lever, a link connecting said member with said bell crank lever, a second link connected with said bell crank lever, and a pin and slot connection between said bell crank lever and the friction wheel of the machine, and spring means for holding said member under tension when said member is in co-acting engagement with a film strip. 70

2. In combination with the shutter of a moving picture projecting machine, a rotatable shaft, a friction clutch including a part rotatable with said shaft and a second part movable with respect to said first part, an arm connected with said second part and engaging said shutter, means between said parts for raising said shutter when the rotation of said shaft reaches a predetermined speed, a strip of film passing behind said shutter, a spring pressed member held in a depressed position by said film, a link connected to said second part and movable therewith, and means between said spring pressed member and said lever for actuating said lever upon the breaking of the film to move said second part with respect to said first part for retracting said arm from engagement with said shutter. 80 85 90 95

In testimony whereof I have affixed my signature.

LUKE KIRAL.
